MANUFACTURE OF SHOES

Original Filed July 23, 1925 2 Sheets-Sheet 2

UNITED STATES PATENT OFFICE.

WILLIAM C. CARD, JR., OF BOSTON, MASSACHUSETTS, ASSIGNOR OF ONE-HALF TO
MALCOLM GREEN, OF NEWTON HIGHLANDS, MASSACHUSETTS.

MANUFACTURE OF SHOES.

Original application filed July 23, 1925, Serial No. 45,584. Divided and this application filed November 16, 1925. Serial No. 69,224.

This invention pertains to machines for marking or making large perforations or cut-outs in sheet material and is herein described with particular reference to its adaptation for use in the making of footwear, the present application being a division of my copending application Serial No. 45,584, filed July 23, 1925.

For making footwear the present machine is of great utility in marking the upper leather (by impressing the latter in accordance with a predetermined contour pattern) to provide a guiding line or mark to assist the stitcher in producing ornamental rows of stitches; for making ornamental cut-out openings; and for various other purposes which will be apparent to the practical shoe maker. As herein disclosed the machine is specifically illustrated and described as arranged to make ornamental cut-outs, that is to say, openings of relatively large area in the upper of the shoe and which are usually defined and set off by marginal rows of stitches.

In accordance with the usual method of making shoe parts, for example, yamps, tips, quarters, etc., having cut-outs, the openings in the material, for example leather, which forms the outer member of said part, are made substantially at the same time that such part is cut, and usually by means of the same dies or patterns which are employed in cutting the part. This outer member thus provided with its cut-out opening or openings is then assembled with the other parts of the upper and with corresponding lining members and stitched to produce the complete upper. At some convenient point in this general operation, the margins of the cut-out openings are furnished with their bordering row or rows which pass through both outer member and lining.

If the lining members for these outer parts are also furnished with cut-out openings prior to assemblage with the corresponding inner parts, it is almost impossible to register the openings of a lining member with those of its mating outer part and in consequence portions of the lining show through the openings in the outer part, greatly detracting from the appearance of the shoe. Furthermore, under this mode of procedure, it is extremely difficult properly

to form the rows of bordering stitches so as to unite the lining to the outer part around the entire margin of the opening. For this reason it has been proposed simultaneously to cut the openings in the outer part and lining after these parts have been assembled, but before lasting, and then to form the bordering rows of stitches. Here again difficulty is experienced, particularly when highly complicated cut-out patterns are employed, since the material between adjacent openings is often very narrow, and when the upper is subjected to any substantial strain or is even handled without especial care, the lining stretches and wrinkles and the openings in the outer part and lining no longer register, and it is practically impossible so to stitch them together as to avoid ragged edges and the exposure of portions of the lining through the openings.

For the above reasons and since the formation of these ornamental cut-out openings, often of large size, greatly weakens the leather or other material forming the outer member of the upper, the lining is commonly left intact and without corresponding cut-out openings and during the subsequent operations of pulling over, bottoming, etc.; the lining is depended upon to carry the strains imposed upon the upper. As the lining is usually of textile fabric which readily stretches in a bias direction, it often fails to prevent overstraining of the upper and consequently shoes provided with cut-outs of large extent are frequently over-size and of distorted shape.

When the shoe thus made is substantially completed, it is necessary to remove the lining corresponding to the cut-outs in the outer member of the upper and this is usually performed manually by the use of a knife blade. This operation requires great skill and care, is slow and expensive at best, and commonly results in damage to a relatively large percentage of the shoes, and even when carefully performed, such a mode of removing the textile lining frequently leaves ragged or frayed edges which detract from the appearance of the finished shoe.

Up to the present time no apparatus known to me has been developed by means of which such cut-outs can satisfactorily be produced, and for this reason manufacturers

of shoes of the very highest grade have generally refused to make shoes of this character in spite of the demand, owing first to the high percentage of damage in producing such shoes by present methods, and secondly to the reluctance of such manufacturers to produce shoes which are in any particular open to criticism.

The principal object of the present invention is to provide for the manufacture of footwear of the class described in a cheap and expeditious manner and without substantial danger of injury and in such a way that the cut-outs do not weaken the upper during the lasting or subsequent processes and at the same time producing cut-outs of better and more sharply defined character than is usual by the ordinary method of production.

In using my improved machine I first stamp, or preferably impress but without actual incision, upon the surface of the leather or other material intended to form the outer surface of the shoe, the outline of the cut-out or cut-outs desired to be formed therein and preferably at the same time I provide a small positioning perforation within the marked area at a point having a definite relation to the contour of the desired cut-out. These marked parts of the upper are then assembled with their corresponding lining members and the other parts and stitched in usual manner to form the complete upper, the marginal stitching of the cut-out being performed at such desired stage in the process as is usual, using the markings or impressions upon the surface of the outer member as a guide in making the row or rows of bordering stitches.

The shoe is now assembled with the inner sole and lasted in usual manner and since the cut-outs have not as yet been formed in the upper the shoe may be lasted with no more difficulty than shoes of ordinary type and without danger of undue stretching or tearing. After the shoe has been substantially completed, those portions of the upper which lie within the marginal stitches defining the proposed cut-out are removed by a punching operation which cuts through both the outer member and the lining in one operation, leaving a clean sharply defined opening.

The improved mechanism herein disclosed comprises as its essentials a work supporting horn or bed plate capable of entering if necessary into the extreme toe tip of the shoe, a presser foot or positioner having substantially the exact shape of the desired cut-out or cut-outs and which may be brought down with resilient pressure upon the outer surface of the upper so as to lie just within the bordering row of stitches, said presser foot preferably having a positioning nib or fit adapted to enter the positioning perfora-

tion above described as initially formed within the area of the proposed cut-out. The provision of this perforation and the corresponding fit on the presser foot is desirable as it enables the operator more quickly and accurately to locate the work relatively to the presser foot, but this perforation and the corresponding fit on the presser foot may be dispensed with if desired since by the exercise of care the operator can position the pressure foot solely by reference to the marginal stitches defining the desired cut-out area.

When the presser foot has been properly positioned by swinging the shoe relatively to the supporting horn, a hollow punch or die of the same contour but very slightly larger than the presser foot and which telescopes over and registers with the latter, is brought down with sufficient force to cut through both leather and lining. The work supporting horn preferably has a resiliently supported cutting bed of a character such that it does not injure the cutting edge of the punch.

Preferably the punch is power driven and controlled by a one revolution clutch so that each depression of the controlling treadle can produce but a single down stroke of the punch.

To facilitate the formation of cut-outs of different shapes in rapid succession, the reciprocating ram which supports and actuates the punch is preferably furnished with a rotary turret capable of supporting a plurality of punches and their corresponding presser feet. This turret may be turned to bring any selected punch with its presser foot into operative relation to the work support and is then held in this adjusted position by suitable retaining means.

The machine is provided with suitable marking punches corresponding in shape and size to the punching dies and these marking punches are adapted to be mounted in the turret in place of the punching dies so that the same mechanism in general may be employed if desired both for marking the material and for removing the marked portions from the finished shoe.

In the accompanying drawings certain steps of the improved process are illustrated by way of example, together with a preferred mechanism useful in performing the process.

In the drawings,—

Fig. 1 is a side elevation, partly in vertical section of a preferred mechanism useful in performing the process herein described;

Fig. 2 is an end elevation from the left-hand side of the device as shown in Fig. 1;

Fig. 3 is an end elevation from the right-hand side of the device as shown in Fig. 1, omitting the fly wheel;

Fig. 4 is a fragmentary elevation from the

left-hand side of the machine as viewed in Fig. 1 to larger scale, showing certain details of the punching die and presser foot;

Fig. 5 is a fragmentary vertical section on the line 5—5 of Fig. 4;

Fig. 6 is a fragmentary plan view of the outer end of the work supporting horn;

Fig. 7 is a fragmentary vertical section on the line 7—7 of Fig. 6;

Fig. 8 is a side elevation of a preferred form of marking punch;

Fig. 9 is a bottom plan view of the punch shown in Fig. 8;

Fig. 10 is a fragmentary vertical section to larger scale substantially on the line 10—10 of Fig. 9;

Fig. 11 is a fragmentary view, partly in vertical section and partly in elevation, illustrating a modified form of marking punch,

together with a form of bed plate or work support useful in performing the marking operation;

Figs. 12, 13 and 14 are views illustrating various steps in the improved process; and

Figs. 15 and 16 are fragmentary views illustrating cut-outs of more complex type.

Referring to the drawings, the numeral 1 (Fig. 1) indicates a base or supporting member provided with pairs of uprights 2, 2^a, and 3, 3^a which support the bearings 4 and 5 in which a horizontal drive shaft 6 is journaled.

At the right-hand side of the machine as viewed in Fig. 1, this shaft is furnished with clutch mechanism 7 of any usual type adapted at will to connect the driving or fly wheel 8 with the shaft 6. This drive wheel 8 normally turns freely with respect to the shaft 6 and is driven continuously from any suitable source of power.

Referring particularly to Fig. 3, the numeral 9 designates a stop dog which in well-known manner normally engages a part of the clutch 7 to hold the clutch parts in disengagement so that the shaft 6 remains at rest. In accordance with the present invention, this dog 9 preferably forms one arm of a bell crank lever pivoted at 10 and having the substantially horizontal arm 11. A latch lever 12 is pivoted at the point 13 upon a suitable part of the frame and this lever is furnished with a slot 14, substantially of L shape. A pin 15 normally engages the horizontal limb of this slot. The pin 15 is carried by the lower end of a link 16 pivotally connected at 17 to the end of the arm 11. A spring 18 tends normally to hold the dog 9 in operative position as shown in Fig. 3, the clutch parts being disengaged. A spring 19 normally tends to retain the link 16 in the position shown in Fig. 3 with the pin 15 disposed in the horizontal part of the slot 14.

A link 20 connects the free end of the lever 12 to a treadle 21 or other controlling

device. When the treadle is depressed the pin 15, by engagement with the horizontal limb of the slot 14, swings the arm 11 downwardly and removes the dog 9 from engagement with its co-operating clutch element, thus connecting the shaft 6 to the fly wheel and causing the shaft to rotate. As the lever 12 continues to move downwardly, the pin 15 escapes into the vertical limb of the slot 14 and the spring 18 immediately returns the dog 9 to its normal position. This return of the dog 9 occurs before the shaft 6 has made more than one revolution so that even though the treadle be retained in depressed position the shaft 6 is stopped at the end of the first revolution and cannot again be clutched to the fly wheel until the treadle has been allowed to rise.

A bracket 22 (Fig. 1) depends upon the upper part of the machine frame and carries a work supporting horn 23 which projects to the left as viewed in Fig. 1 between the legs 2 and 2^a. Preferably, as shown in Fig. 6, this horn terminates in a more or less pointed or rounded end adapted to enter the toe portion of a shoe and its outer part is furnished with a recess 25 in which a plate 26 is positioned. This plate is resiliently supported by means of springs 27 or equivalent devices and carries the bed plate 28. Preferably the bed plate is formed of some non-metallic material, for example, indurated fiber or wood, which will not seriously dull the edge of the punching die when the latter is brought down against it. Preferably the upper surface of this bed is upwardly convex, in order that it may better conform to the inner surface of the shoe and is furnished at a suitable point with a small recess 27^a for the reception of the positioning tip of the presser foot hereinafter described.

The left-hand side of the machine frame as viewed in Fig. 1 carries a vertically reciprocating ram 29 sliding in spaced vertical guideways 29^a. The inner side of this ram is furnished with a housing 30 which receives an eccentric 31 mounted upon the end of the shaft 6. Suitable wear plates 32 and 33 are arranged at the top and bottom of this housing, such wear plates being replaceable when seriously worn. The arrangement described is such that each rotation of the shaft 6 produces a downward and upward reciprocation of the ram 29.

The forward face of the ram 29 is furnished with a projecting axle boss 34 which supports a disc-like turret 35. This turret turns freely upon the boss 34 and is retained thereon by means of a collar 36. The right-hand face of the turret disc 35 is provided with a plurality of symmetrically spaced recesses 37 and a retaining pin 38, carried by a resilient support 39, is adapted to engage any selected one of these pins to hold the turret in adjusted position.

The turret is provided with a plurality of radial socket openings in its circumferential edge extending inwardly to the desired depth and adapted to hold punch supporting sleeves 40 which are removably retained in their respective sockets by means of set screws 41. Each sleeve 40 (Fig. 5) projects beyond the edge of the turret disc and its projecting end is screw threaded for engagement with an internally threaded boss 42 projecting from the rear face of a hollow punch 43. This punch is furnished with a flange 44 projecting from its lower face, such flange being sharpened to provide a cutting edge and being of a contour geometrically similar to that of the desired cut-out.

The punch supporting sleeve 40 forms a guide for the supporting stem 45 of an indicator or work positioning presser foot 51 associated with the punch. The inner end of the stem 45 is furnished with an axial projection 46 adapted to enter and to position a coiled spring 47 which is seated in the inner end of the sleeve 40 and which normally tends to project the stem 45 from the outer end of the sleeve. A stop member 48, preferably extended to form a handle, is secured to the inner part of the stem 45 and projects out through an elongate slot 49 in the side wall of the sleeve 40 and through a corresponding slot 50 in the turret 35. This handle 48, by engagement with the lower end of the slot, limits downward movement of the stem 45 and at the same time forms a convenient means for manually lifting the stem and the presser foot 51 to permit the work to be placed on the work support.

The presser foot 51 is secured to the outer end of the stem 45. This presser foot preferably consists of a flat plate having a marginal edge 52 geometrically similar to the contour of the corresponding punch 43 but slightly smaller so that the cutting edge 44 of the punch may telescope over the presser foot. Preferably the edge of the presser foot is bevelled as at 53 in order to facilitate accurate positioning of the work with respect to such edge. The outer face of the presser foot 51 is furnished with a projecting positioning tit 54 and when the punch and presser foot are in operative position, this tit is vertically aligned with and adapted to enter the pocket 27^a in the bed plate 28.

Referring to Figs. 8, 9, and 10, the numeral 55 indicates a block or backing member forming part of a marking punch, such block being provided with a stem 56 of a diameter substantially equal to the external diameter of the punch supporting sleeve 40 above described and which may be substituted for such sleeve when desired. The block 55 supports a face plate 57, having a ridge-like projection or stamp 58 upon its

lower surface. The edge of this projection or ridge is preferably blunt and is of a contour exactly similar to that of the desired cut-out. In Fig. 9, this ridge or projection is indicated by way of example as of 70 a diamond-shaped contour.

Within the area defined by a ridge 58, a perforating punch 59 is arranged. This punch projects beyond the plane of the outer edge of the ridge 58 to a distance such that when this marking punch is brought down upon the surface of the work the perforating punch 59 will form a small perforation through or substantially through the work. The punch 59 is preferably located at the axis of symmetry of the figure defined by the ridge 58, although its exact position is not essential.

One convenient mode of forming the ridge 58 is to make the face plate 57 of sheet metal and to stamp up the ridge 58 from the back side of the plate, filling in the space 59^a inside of said ridge if necessary, with solder or other suitable material as indicated at 60 in Fig. 10.

In Fig. 11 a modified marking punch is indicated comprising block 55, the stem 56, and a face plate 57^a. In this instance the face plate is provided with a plurality of raised figures or stamps 58^a, 58^b and 58^c, respectively which may be of like or different contours. In this instance, the perforating punch 59^a is arranged at the center of the raised stamping ridge 58^c, although it is contemplated that it may be located within either one or the other of such raised figures.

In Fig. 11 a stamping bed 62 is also illustrated. This bed is provided with a flat upper surface for use when marking the work. This bed plate may be substituted for the bed plate 28 by removing the latter from its support 26 and sliding the bed plate 62 into position thereon. This bed plate 62 is furnished with a recess 63 for the reception of the perforating punch 59.

As a specific example of the mode of using my machine, I first cut by ordinary methods the outer member of the shoe part which is to be provided with the cut-out. For example, as shown in Fig. 12, this part may be a vamp 64 having the usual matching notches 65 in its edge. I then place in any one of the sockets in the turret of the machine a marking punch of suitable form, such for example, as the punch 55 shown in Fig. 8 and after laying the vamp 64 upon the punching bed plate 62, positioning it properly by means of the notches 65 and co-operating marks or pins on the upper surface of the bed plate I depress the treadle 21, thus causing the ram and turret to descend, bringing the stamping ridge 58 forcibly down upon the vamp at the desired point. If desired, the edge of the stamping projection 58 may be furnished with suit-

able pigment or coloring material so as to leave a distinct mark upon the vamp. Preferably I omit this coloring material and merely impress the contour of the marking 5 punch upon the surface of the material but preferably without cutting or breaking the surface of the latter. Since the perforating punch 59 projects beyond the plane of the edge of the stamping punch it passes 10 through the material forming a small perforation therein.

The vamp now has the general appearance indicated in Fig. 12, having on its outer surface the outline 66 of the desired 15 cut-out with the centrally disposed perforation 67. This vamp is now assembled with a corresponding lining 64^a (Fig. 13) and with the other parts of the upper by the usual methods. Either before or after assemblage with the other parts of the upper, the vamp 64 with its lining 64^a is provided with a row of stitches 68 closely bordering the impressed outline of the cut-out. This line of stitches passes through both the outer members of the lining of the part being operated on. More than one of such rows 25 of stitches may be provided if desired.

The upper is now assembled with the bottom parts of the shoe and the shoe is completed in the usual manner and by the usual processes. When the shoe is substantially complete and ready for shipment, the operator places a cut-out punch 43 with its corresponding presser foot in the turret in the machine, such punch and presser foot having the contour of the desired cut-out as previously impressed upon the surface of the upper. The shoe is then slipped over the work supporting horn 23, the presser foot 51 first being raised by means of the handle 48. The presser foot is now allowed to drop, the work being so moved that the projecting tit 54 enters the perforation 67 in the upper and the shoe is swung about this tit as an axis until the edge 52 of the presser foot registers exactly with the impressed design upon the shoe upper.

When the shoe has thus been positioned, the treadle is depressed, moving the ram 29 downwardly and thus causing the punch 43 to telescope over the edge of the presser foot. Since the engagement of the handle 48 with the slot 49 prevents any relative 55 angular movement of the punch and the presser foot, and since the punch and presser foot are initially oriented so that their corresponding edges are exactly parallel, the punch is free to move down over the edge 52 of the presser foot into engagement 60 with the material and in such further downward movement passes through both the outer member of the lining and the upper, thus at one operation cutting out the material within the bordering row of 65 stitches and leaving a sharply defined cut-

out opening. By the use of the positioning perforation 67 and the corresponding positioning tit 54 on the presser foot, great accuracy may be secured with comparatively little care on the part of the operator so that relatively unskilled help may be employed in the manufacture of shoes of this class.

Since the turret permits punches of various shapes to be mounted at the same time upon the ram, the operator may quickly substitute one punch for another as the character of the work may demand and as above pointed out, if desired, the same machine may be used, both for marking the uppers and for cutting them out after the completion of the shoe. Preferably, however, separate machines will be employed for convenience, since the uppers are usually cut and otherwise prepared at a point remote from that at which the shoes are completed, ready for shipment.

In Fig. 15 a shoe is illustrated having a series of cut-out openings 70 arranged closely adjoined to one another while Fig. 16 shows a pump also having closely spaced openings 71. While shoes having such complex and lace-like cut-out portions can readily be made by the method and apparatus herein disclosed, I know of no other satisfactory way in which such elaborate patterns can be produced.

While a preferred embodiment of the means for performing the above described operation has herein been shown by way of example, it is understood that various changes and modifications may be made therein as circumstances may warrant and as the character of the work may demand but without departing from the spirit of the invention.

I claim:

1. A machine of the class described comprising a work support, a punch reciprocable toward and from the work support, and a device normally spaced a substantial distance in advance of the cutting edge of the punch and movable relatively to the punch toward and from the work and engageable with the work when the punch is retracted to indicate the area of the work which will be removed by the punch when the latter makes its working stroke.

2. A machine of the class described comprising a work support, a punch reciprocable toward and from the work support, an indicator device normally spaced from the cutting edge of the punch in the direction of operative movement of the latter, said device having a contour similar to that of the cutting edge of the punch, said device engaging the work when the punch is retracted thereby to indicate the line of engagement which the cutting edge of the punch will make with the work when the punch makes

its working stroke, and means for manually lifting the indicator device from the work.

3. A machine of the class described comprising a work support, a retractable positioning foot normally engaging the work resting upon the work support, said foot having an edge constituting a guide for placing the work upon the support, a punch having a cutting edge normally retracted 10 and spaced from the foot, said cutting edge being disposed closely parallel to the vertical plane of said edge of the positioning foot, and means for moving the punch relatively to said positioning foot to cut the material 15 along a line parallel to the guiding edge of said foot.

4. A machine of the class described comprising a work support, a manually retractable positioning foot normally yieldingly engaging the work resting upon the work support, said foot having an edge contour like that of the opening to be made in the work and constituting a guide for placing the work upon the work support, a punch having 25 a cutting edge geometrically similar to that of the foot, the punch and foot normally being spaced from each other, means maintaining a similar orientation of the punch and foot, and means for moving the punch 30 relatively to the positioning foot and toward the work support to cut through the work resting thereon.

5. A machine of the class described comprising a work supporting horn, a ram movable toward and from the work engaging surface of the horn, a punch carried by the ram, said punch normally being spaced from the work supporting arm and having a contour like that of the opening to be made in 35 the work, and a positioning device normally spaced from the punch and engageable with the work prior to operative movement of the punch and determining the orientation of the punch relatively to the work during operative movement of the latter, said positioning 45 device having a contour similar to that of the punch.

6. A machine of the class described comprising a work support, a positioning device normally engaging the work resting upon the support, said positioning device having a contour of the shape of the opening to be made in the work, a punch of a contour geometrically similar to that of the positioning device, said punch normally retracted from the work support, said punch being normally movable relatively to the positioning device toward and from the work support, means to maintain similar orientation of the punch 55 and positioning device, and means for actuating the punch to remove from the work a piece corresponding in size and shape to the contour of the punch.

7. A machine of the class described comprising a work supporting horn, a ram mov-

able toward and from the horn, a yieldable work positioning presser foot carried by the ram and normally engaging work resting upon the horn, manually operable means for lifting the presser foot relatively to the ram, 70 and a hollow punch whose cutting edge has a contour geometrically similar to that of the presser foot, said punch being mounted upon the ram to move therewith toward the horn and when so moving telescoping over the 75 presser foot, the punch normally being spaced a substantial distance from the presser foot.

8. A machine of the class described comprising a work supporting horn, a ram movable toward and from the horn, a yieldable presser foot carried by the ram and normally engaging work resting upon the horn, manually operable means for lifting the presser foot relatively to the ram, said presser foot 80 having an elongate stem, a tubular punch carrier sliding longitudinally of said stem, and a hollow punch mounted upon the end of said carrier, said punch normally being spaced from the presser foot, the cutting edge 85 of said punch having a contour geometrically similar to that of the presser foot and of slightly larger dimensions to permit it to pass down over the presser foot when the punch carrier is moved relatively to the 90 presser foot stem.

9. A machine of the class described comprising a work support, a vertically movable ram, means for reciprocating the ram, a punch supporting sleeve carried by the ram, an annular punch secured to the lower end 100 of the sleeve, a longitudinally slideable stem within the sleeve, a presser foot carried by the stem, said presser foot being normally positioned a substantial distance in advance 105 of the cutting edge of the punch and having a thin edge portion of a contour geometrically similar to that of the punch, and means preventing relative rotation of the stem and sleeve.

10. A machine of the class described comprising a work support, a vertically movable ram, means for reciprocating the ram, a punch supporting sleeve carried by the ram, an annular punch secured to the lower end 115 of the sleeve, a longitudinally slideable stem within the sleeve, a presser foot secured to the lower end of the stem, the presser foot normally being spaced a substantial distance 120 in advance of the cutting edge of the punch, the contour of the presser foot being geometrically similar to that of the punch, the presser foot being of slightly less dimensions than the punch to permit the latter to telescope over it, and means to prevent relative 125 turning of the punch and presser foot.

11. A machine of the class described comprising a work supporting horn, a vertically movable ram, a punch supporting sleeve carried by the ram, a hollow punch mounted 130

- upon the lower end of the sleeve, a presser foot stem telescoping in the sleeve, a spring urging said stem toward the work support, means for preventing relative rotation of the 5 sleeve and stem, and a presser foot secured to the lower end of the stem and normally disposed substantially below the normal position of the punch, the contour of the presser foot being geometrically similar to 10 that of the punch.
12. A machine of the class described comprising a work supporting horn, a vertically movable ram, a punch supporting sleeve carried by the ram, a hollow punch mounted 15 upon the lower end of the sleeve, a presser foot stem telescoping in the sleeve and normally projecting downwardly below the cutting edge of the punch, a spring urging said stem toward the work support, a lifting handle secured to the stem and projecting out through a vertical slot in the wall of the sleeve, and a presser foot secured to the lower end of the stem, the punch being of such size as to permit it to telescope over 20 the presser foot.
13. A machine of the class described comprising a work support, a vertically movable ram, means for reciprocating the ram, a punch supporting sleeve carried by the ram, an annular punch secured to the lower end 25 of the sleeve, a longitudinally slid able stem within the sleeve, said stem normally projecting downwardly below the cutting edge of the punch, a presser foot secured to the lower end of the stem, the contour of the 30 presser foot being geometrically similar to that of the punch, a positioning tit projecting from the under surface of the presser foot, and means to prevent relative orientation of the presser foot and punch.
14. A machine of the class described comprising a work support, a vertically movable ram, means for reciprocating the ram, a punch supporting sleeve carried by the ram, an annular punch secured to the lower end 35 of the sleeve, a longitudinally slid able stem within the sleeve, said stem normally projecting downwardly below the punch, a presser foot secured to the lower end of the stem, the edge contour of the presser foot being geometrically similar to the 40 contour of the cutting edge of the punch, a positioning tit projecting downwardly substantially at the axis of symmetry of the 45 presser foot, and means to prevent relative orientation of the punch and presser foot.
15. A machine of the class described comprising a work support, a vertically reciprocating ram, means for actuating the ram, a 50 turret pivotally supported by the ram, a plurality of punches, each provided with an associated positioning device normally disposed in advance of and spaced from its respective punch, mounted on the turret, and means for retaining the turret in adjusted 55 position with a selected punch disposed in operative relation to the work support.
16. A machine of the class described comprising a work support, a vertically reciprocating ram, means for actuating the ram, a 60 turret mounted upon the ram and pivoted to turn upon a horizontal axis, spaced radially extending punches carried by the turret, the cutting edges of the several punches being of different contour, a presser foot associated 65 with each punch, said presser foot normally being disposed in advance of and spaced from its respective punch, the contour of each presser foot being geometrically similar to that of its respective punch, and means 70 for retaining the turret in desired position of angular adjustment with a selected punch and its associated presser foot in operative position.
17. A machine of the class described comprising a reciprocating punch, a device associated with the punch and engageable with the work when the punch is retracted to indicate the exact area of the work which will be engaged by the punch in making its 75 working stroke, and a work support having a yieldable bed opposed to the punch.
18. A machine of the class described comprising a reciprocating punch, a device associated with the punch and engageable with the work when the punch is retracted to indicate the exact area of the work which will be engaged by the punch in making its 80 working stroke, a work supporting horn, and a spring supported bed carried thereby 85 to receive the blow of the punch.
19. A machine of the class described comprising a reciprocating punch, a device associated with the punch and engageable with the work when the punch is retracted to indicate the area of the work which will be engaged by the punch in making its 90 working stroke, and a work supporting horn of a size permitting it to enter into the toe portion of a shoe.
20. A machine of the class described comprising a reciprocating punch, a device associated with the punch and engageable with the work when the punch is retracted to indicate the exact area of the work which will be engaged by the punch in making its 95 working stroke, a work supporting horn, and a bed having a convex upper surface mounted upon the horn.
21. A machine of the class described comprising a reciprocating punch, a device associated with the punch and engageable with the work when the punch is retracted to indicate the exact area of the work which will be engaged by the punch in making its 100 working stroke, a work supporting horn of a size permitting it to enter into the toe portion of a shoe, and a bed of relatively 105 soft material mounted upon the horn in position to oppose the cutting edge of the punch.

22. A machine of the class described comprising a reciprocating punch, a device associated with the punch and engageable with the work when the punch is retracted to indicate the area of the work which will be engaged by the punch in making its working stroke, a work support, and power means for actuating the punch including a one revolution clutch.
23. A machine of the class described comprising a reciprocating punch, a device associated with the punch and engageable with the work when the punch is retracted to indicate the exact area of the work which will be engaged by the punch in making its working stroke, a work support, punch actuating means including a clutch having a normally operative stop dog, a controller movable in a predetermined direction to withdraw the dog and thereby to permit the punch actuating means to move the punch toward the work, and means automatically releasing the dog to allow it to resume normal position as the controller nears one limit of its path of movement.
24. A machine of the class described comprising a reciprocating punch, a device associated with the punch and engageable with the work when the punch is retracted to indicate the exact area of the work which will be engaged by the punch in making its working stroke, a work support, punch actuating means including a clutch provided

with a normally operative stop dog, a treadle, and connections between the treadle and dog comprising interlocking parts normally operative to transmit motion from the treadle to the dog whereby to move the latter out of operative position, said interlocking parts automatically disengaging as the treadle nears the limit of its operative movement thereby releasing the dog and allowing it to return to normal position.

25. A machine of the class described comprising a reciprocating punch, a device associated with the punch and engageable with the work when the punch is retracted to indicate the exact area of the work which will be engaged by the punch in making its working stroke, a work support, punch actuating means including a clutch provided with a normally operative stop dog, a treadle, a lever having a substantially L shaped slot therein, a link connecting the treadle with the end of the lever, and a link connected to the stop dog, said link having a pin normally disposed in the horizontal limb of the slot in said lever whereby to transmit movement from the treadle to the dog, said pin slipping into the upright limb of the slot as the lever swings thereby releasing the dog, and a spring tending to hold the dog in normal position.

Signed by me at Boston, Massachusetts,
this fourteenth day of November, 1925.

WILLIAM C. CARD, JR.
